[57] **ABSTRACT**

A key-operated lock having a locking bolt or tongue having a latch position and a bolt locked position, and including a locking plug with means for holding the locking plug in either tongue-locked or tongue-free condition; the locking tongue in bolt locked position extending to a greater than normal extent to present a flat flush surface to the door jamb to prevent retraction of the tongue by means of an instrument at the front of the door.

FIG. 14

LOCK WITH SAFETY BOLT

BACKGROUND OF THE INVENTION

Locks of the class described which are usually referred to as door locks, have a tongue normally extending from a casing for engagement in a socket or keeper on a frame of the closure in which the bolt is withdrawn inwardly of the casing to a release position, and a key operated member of the oscillatable plug type accessible at either or both sides of the casing for locking and unlocking the bolt so that it can be opened by means of the door handle. These locks are commonly constructed as morticed locks, although the invention is not so restricted.

These locks are commonly relatively complicated and expensive both to manufacture and install, and in many cases it is possible to open them by means of a stiff implement merely thrust into a space between the edge of the door and the door jamb or frame because the tongue has an inclined surface so that the door can be closed without actuating the handle as is well known.

It is the object of the present invention to provide a very simple and inexpensive lock of the kind described which has a tongue which is impossible to retract by means of an implement thrust inbetween the door casing and the casing of the lock itself, i.e., the edge of the door, because a flat surface is presented, not an inclined surface.

BRIEF DESCRIPTION OF THE DRAWING

FIG. 1 is a view of one form of the lock showing the same in bolted and locked condition, a side plate being removed;

FIG. 2 is a similar view but with parts in section illustrating the lock in unlocked condition;

FIG. 3 is a view illustrating the side plate for the lock casing which is omitted in FIGS. 1 and 2;

FIG. 4 is a partial edge view thereof looking in the direction of arrow 4 in FIG. 3;

FIG. 5 is a partial rear view of the side plate of FIG. 3, and showing the thumb turn cam;

FIG. 6 is a view similar to FIG. 1 showing a modification;

FIG. 7 is an edge view thereof looking in the direction of arrow 7 in FIG. 6;

FIG. 8 is a view similar to FIG. 6 but showing the lock in unlocked condition;

FIG. 9 is a perspective view of a form of tongue or bolt;

FIG. 10 is a bottom plan view of FIG. 8;

FIG. 11 is a view similar to FIG. 6 showing a further modification;

FIG. 12 is a view similar to FIG. 8;

FIG. 13 is a perspective view of the tongue of FIGS. 11 and 12; and

FIG. 14 is a perspective view of a tongue retractor.

PREFERRED EMBODIMENTS OF THE INVENTION

In FIGS. 1 and 2, the lock is provided with a case 10 having a front plate 12. The case forms an enclosure one of the side plates of which is indicated at 14 in FIG. 3 and is omitted from FIGS. 1 and 2 in order to show the mechanism. A door handle shaft fits in an opening at 16 turning an oscillating element 18 provided with a pair of radial arms 20 and 22.

The arm 22 is provided with a spring-pressed ball connection 24, FIG. 2; with respect to member 18 so that if a wrench is put on the handle the square shaft will turn the member 18 forcing back the ball at 24 so as to fail to operate the lock by force. If desired, an opening at 25 in the bottom 26 of the casing 10 may provide an opening for motion of arm 22 in a clockwise direction therethrough, also thereby turning arm 20 in a clockwise direction to retract bolt or tongue 30.

A tongue or a bolt generally indicated at 30 is provided with a chamfered head 32 which extends through an opening 34 in the front plate 12. This also acts as a guide for the tongue or bolt, at least at the forward end portion thereof which terminates in an enlarged shoulder 36. As shown in FIG. 1 this prevents any further extension of the tongue 30 outwardly to

the left. As a matter of fact there may be a pair of shoulders 36, one at the top of the tongue and one at the bottom thereof. The tongue is spring-pressed to the left by a spring 40 contained in a recess therein and operating against one end of a pin 42, the other end of which may rest against a rear wall 44 of casing 10, see FIG. 2. The tongue or bolt has spaced ears 41 and 43 for actuation by arm 20, to move the tongue in either direction.

The opposite end of the tongue or bolt terminates in a relatively smaller head 48 located in guideways 50, 52 so as to slide therein, and looking for instance at FIG. 2 it will be seen that the chamfered head 32 of the tongue or bolt 30 is capable of spring-resisted retraction from the position shown in FIG. 2 to a position wherein the extreme forward edge of the head of the tongue may be aligned with respect to the outer surface of front plate 12 of casing 10 to open the door, as by the handle in opening 16.

There is an oscillating plug indicated at 60 for the purpose of locking the tongue or bolt as in the FIG. 1 position. This plug is provided with a downwardly extending projection 62 so that when it is turned in a counterclockwise direction from the FIG. 2 free position to the FIG. 1 locked position, the abutment 62 will lie behind the shoulder 63 formed in head 54, thus clearly locking the bolt or the tongue in the position shown in FIG. 1, preventing any motion to the right and at the same time the shoulders at 36 prevent any further motion to the left. A simple spring 64 may be utilized to hold the plug in the position shown in FIG. 1 and by means of the bent arm 66 thereof it can also be used to hold it in its free condition, see FIG. 2.

The plug 60 is pivoted on a pin 70 and is moved into the FIG. 1 position by means of a cam 72, this cam being operated by a key inserted in key slot 74 as will be clear to those skilled in the art, and it will be also seen that the plug 60 is held in the FIG. 1 position thereby, but when the key is turned in a clockwise position, the cam 72 turns also freeing the plug 60 and at its opposite stroke causing the same to move in a clockwise direction about pivot 70, so that the handle in the square slot 16 may then be turned to open the door or other closure.

It is preferred that the plug 60 should also have another abutment 80 at its opposite end for engagement with the left edge of head 48, see FIG. 2, when the plug 60 is in tongue-free condition, preventing the tongue from moving to the left, also, a locking bolt 84 drops down behind shoulder 36, see FIG. 2, preventing the tongue or bolt 30 from moving any further to the left than is shown in FIG. 2, this being an intermediate position in which the chamfered portion of head 32 is either aligned with or retracted within the aperture 34. The reason for this is that the head of the tongue or bolt besides the chamfered portion also has a flat surface 90 on it and when in the FIG. 1 position thereof this flat surface 90 extends to the left beyond the face plate 12, so that an implement thrust in between the face plate and the door jamb cannot contact the chamfered surface on the head 32, but is engaged by the flat surface 90 and this thereby prevents the tongue from being retracted.

The bolt 84 is operated by a pivoted member 92 having a pair of arms 94 and 96, the arm 94 extending into a yoke 100 in the plug 60, so that it will be seen that the member 92 is moved both up and down by plug 60 as the latter is turned by means of the key and under influence of cam 72, or by thumb turn cam 200.

There may also be utilized a spring-pressed member 101 having an end 102 which may be pushed into the position shown in FIG. 1, preventing the tongue or bolt 30 from being moved exteriorly of casing 10 by any means so that even if the lock should be picked, the pin 102 which of course is operated from inside the door, prevents the tongue from retraction to open the door.

Thus it is seen that the tongue or bolt 30 provides a night bolt effect which cannot be jimmied; the pin 102 prevents opening of the lock if the lock at 75 should be picked; and at

the same time that the door is unlocked, the tongue or bolt latches the door when it is shut but it can be retracted for opening the door by the handle in the opening 16. This can also be done by projecting a finger or thumb latch through the opening at 25.

FIGS. 6, 7, and 8 show a modification of the device as shown in FIGS. 1 and 2. In this case the plug 60a is turned directly by a rim cylinder at 112 instead of by the cam. A lost motion connection 113 comprises a spring-pressed pin in the bolt 60a having an end in a slot in the rim cylinder. This permits a small amount of play before actuation of the latch bolt, allowing closing of the door by simply pulling on the knob without the knob turning. A spring-pressed detent 114 is utilized selectively in either of the recesses 116 and 118 to hold the plug 60a in locking or free condition. Plug 60a has a yoke at 100a for operating the pivot member 94a and the latch 84a as previously described.

However the plug 60a, although locking the tongue or bolt 30a by means of a shoulder 62a as before, does not have a shoulder comparable to that at 80 in FIGS. 1 and 2 but instead reliance is placed solely on the bolt 84a. However the tongue is substantially the same as before described having a flat 90a to prevent jimmying and it has projections at 43a for actuation by arm 20a of the oscillating member 18a substantially the same as previously described. The tongues 30 and 30a can be inverted for right and left hand swinging of the door to which the lock is attached.

As seen in FIG. 7, the side plates 120 and 122 are chamfered at their upper and lower edges as at 124 and 126 so that the entire housing can be placed in the mortise, made largely by a drill at least at the ends of the mortise rather than by necessitating the formation of a square mortise as in the prior art. Otherwise the lock in FIGS. 6 to 10 inclusive operates in a similar manner to the lock in FIGS. 1 and 2 and the corresponding numerals correspond to those of FIGs. 6 to 10.

A further modification is shown in FIGS. 11 to 14 inclusive and in general the parts here operate as in FIGS. 1 and 2, but locking bolt 84 is here omitted. The parts in general are indicated by the same reference characters as before, utilizing the lower base b. Lug 62b on the plug 60b extends into a notch similar to the shoulder 63b and the locking member 80b locks behind a shoulder 48b for the same purpose and reasons as explained before with respect to FIGS. 1 and 2. A cam 72b which is utilized to operate the plug 60b as before described 45 and the bolt and tongue 30b acts the same as previously. The spring at 130 has been changed to some extent normally holding the tongue or bolt 30b in the latching condition shown in FIG. 12 and moving the same to the locked condition in FIG. 1 when the plug 60b is moved as by cam 72b as will be clear. In 50 this case the square opening 16b for the handle moves an actuator, see FIG. 14, indicated as at 132, and this operates to bear against an edge 134 on the tongue or bolt 30b to move the bolt to the right so as to open the door. Conversely it also moves the same in the other direction when the handle is turned in the opposite direction and the member 132 bears

against the surface at 136. The tongue 30b is also capable of being placed in either condition for right or left hand opening of the door in which the mortise is located.

It will be seen that this invention provides a mortise lock of the kind described having very few parts as compared to the normal lock commercially in use at the present time. It is substantially jimmie-proof and in some cases pick-proof especially when the element or pin 102 is utilized to lock the door from the inside.

10 This lock essentially has three positions. One of these positions is as shown in FIGS. 1, 6, and 11 wherein the door is not only locked but bolted; an intermediate position shown in FIG. 2 for instance and also in FIGS. 8 and 12 where it is latched but not locked, and the third position where the respective tongues 30 and 30a are retracted in order to allow opening of the door.

An alternate method of locking is by holding bolt 30 in retracted position with the door open, actuating the thumb turn cam 200, closing the door, and returning bolt 30 to closed 20 position with the door handle. This eliminates the usual locking buttons in the front plate of the lock.

I claim:

1. A lock for securing together two structures including a latch on one structure and a keeper on the other structure, said latch comprising a movable tongue, a head on the tongue, a housing for the tongue, the head of the tongue having positions extending from said housing into the keeper to secure the structures, and a retracted position on the housing to free the structures, a movable element having positions for locking the tongue against retraction and for freeing the tongue so that it is retractable, means to retract the tongue when free, means to move the tongue to extended position, said head having a chamfer at its extreme end and a surface portion adjacent the chamfer that is substantially parallel to the direction of motion of the tongue, interengaging means between the element and tongue for locking the tongue in an extended position wherein the said surface portion of the tongue overlaps both structures,

separate means to hold the tongue in an intermediate extending position with the surface portion retracted, and interengaging means between the element and said separate means actuating the latter to tongue holding position upon motion of the element to tongue-free position, said element being oscillatable and said separate means being movable during the oscillating motion of the element in a rectilinear direction, said tongue including a shoulder preventing motion of the tongue past its full extended position, said separate means lodging forwardly of the shoulder, when the tongue is retracted to its intermediate position.

2. The lock of claim 1 including releasable means yieldingly holding said oscillatable element selectively in either of its positions.
